UNITED STATES PATENT OFFICE.

ROBERT H. McCARTHY, OF MADELIA, MINNESOTA.

INTERNAL-COMBUSTION ENGINE.

1,154,329.

Specification of Letters Patent. Patented Sept. 21, 1915.

Application filed September 26, 1914. Serial No. 863,682.

To all whom it may concern:

Be it known that I, ROBERT H. McCARTHY, a citizen of the United States, residing at Madelia, in the county of Watonwan and 5 State of Minnesota, have invented certain new and useful Improvements in Internal-Combustion Engines, of which the following is a specification, reference being had to the accompanying drawings.

10 This invention relates to internal combustion engines, and has for its primary object to provide an engine of this character capable of developing the power of the ordinary four cylinder gas engine but in which only 15 two engine cylinders are employed.

In its more specific aspect, the invention embodies opposed cylinders, in each of which a piston is mounted to reciprocate, a common crank shaft, and improved means for 20 connecting the pistons to said crank shaft.

The invention has for a further object to provide an internal combustion engine of the above character which is extremely simple in its construction, highly efficient and durable 25 in practical operation, and capable of generating a high working power from a minimum consumption of the propelling fluid.

With the above and other objects in view, the invention consists in novel features of 30 construction, combination and arrangement of parts as will be hereinafter referred to and more particularly pointed out in the specification and claims.

For a full understanding of the invention, reference is to be had to the following description and accompanying drawings, in which—

Figure 1 is a longitudinal section through an internal combustion engine embodying 40 the present invention; Fig. 2 is a plan view thereof, both of the cylinders being shown in section; Fig. 3 is a view similar to Fig. 1 showing the positions of the pistons in the respective cylinders reversed; and Fig. 4 is 45 a section taken on the line 4—4 of Fig. 2.

Referring in detail to the drawings, 5 designates the opposed engine cylinders which are mounted upon a suitable base indicated at 6. Each cylinder is provided 50 with a water jacket 7, and the ends of the cylinder are closed by the heads 8. A piston 9 is mounted to reciprocate in each of the cylinders 5, and is provided adjacent its opposite ends with a series of peripheral packing rings 10. These packing rings and the heads 8 render the ends of the cylinder ab-

solutely air tight. The central portion of each piston 9 is preferably hollow and through the same the transversely disposed wrist pins 11 extend, the ends of said pins 60 projecting through longitudinal slots 12 in the opposite walls of the cylinder 5. The top of the cylinder is formed with an opening which is closed by a cap plate 13. By removing this plate, the wrist pins 11 may 65 be removed when it is desired to remove the piston from the cylinder.

14 designates the crank shaft which is arranged between the engine cylinders and suitably incased. This shaft is provided 70 with the spaced cranks 15. To the ends of each of the wrist pins 11 rods 16 are rigidly fixed at one of their ends. These rods which are thus connected to the respective pistons extend inwardly toward the crank shaft and 75 are connected thereto by means of the connecting rods 17, said rods being loosely connected at their opposite ends to the cranks 15 of the engine shaft and to the rods 16 respectively. It will be observed that these 80 latter rods are movable through the walls of the water jackets 7 of the engine cylinders.

Each of the engine cylinders is provided at each end with an intake port 18 on one side and upon its opposite side with an exhaust port 19. The intake ports are connected by a common supply pipe with a carburetor or other suitable gas generator. Referring now to Fig. 2 wherein I have indicated the operations which have taken place 85 in the respective engine cylinders, it will be noted that the explosion has occurred in the inner end of one cylinder and the piston therein has been moved to exhaust the burnt 90 gases from the opposite end of the cylinder. In this movement of the piston, the crank shaft 14 is, of course, turned and through the medium of the rods 16 and 17, the other piston is moved into the inner end of its 95 cylinder and compresses the charge which has been previously admitted thereto from the intake port 18. In this movement of the latter piston, the gases are drawn into the other end of the cylinder. The explosion now takes place in the inner end of this 100 latter cylinder, the rotation of the crank shaft 14 being thus continued and the charge in the opposite end of the cylinder compressed. In the other cylinder, the burnt 105 gas is being exhausted from the inner end thereof, while the charge is being drawn into the outer end of the cylinder. Upon the 110

completion of the next half revolution of the engine shaft, the compressed charge in the one cylinder is exploded, while compression takes place in the outward movement of the piston in the other cylinder. It will thus be seen that there is an explosion in each half revolution of the engine shaft, the explosion taking place in the opposite ends of each cylinder alternately with respect to each other.

From the foregoing description taken in connection with the accompanying drawings, it will be seen that I have produced a very simple and efficient engine structure, whereby a high degree of operating energy may be obtained. The engine may be, therefore, compactly and inexpensively constructed, thus admitting of its use in connection with automobiles, traction engines, and similar vehicles. It will also be seen that there is a direct longitudinal thrust from each of the pistons by reason of the rigid connection of the rod 16 thereto, which is converted into a rotary movement of the crank shaft 14 by means of the connecting rods 17. As the engine cylinders are absolutely air tight, loss of compression is effectually precluded. My improved engine is also very durable in its construction, and not liable to easily get out of order.

While I have above described the preferred form, construction, and arrangement of the several elements employed, it will be understood that the device is, nevertheless, susceptible of considerable modification therein, and I therefore reserve the privilege of resorting to all such legitimate changes as may be fairly embodied within the spirit and scope of the invention as claimed.

What is claimed is:

1. In an internal combustion engine, op-

posed engine cylinders, a piston to operate in each of said cylinders, each cylinder being provided with a water jacket, a transversely disposed wrist pin centrally connected to each piston and projecting from opposite sides thereof, each of the cylinders being provided in each end with an intake 50 port and an exhaust port, an engine shaft provided with spaced cranks, thrust rods rigidly connected to the ends of each wrist pin and movably disposed through the walls of the water jacket of the engine 55 cylinder, and connecting rods pivotally connected at one of their ends to said thrust rods, the connecting rods which are connected to the thrust rods on each side of the engine being pivotally connected at 60 their other ends to the respective cranks of the engine shaft.

2. In an engine of the character described, opposed cylinders, a piston to operate in each of said cylinders and provided with wrist pins, the cylinder wall having longitudinal slots in opposite sides through which said wrist pins extend, each of the cylinders being provided with a water jacket, longitudinal rods slidably 70 mounted in the walls of the water jackets and connected at one of their ends to said wrist pins, a power shaft having spaced cranks extending upon the same side of its axis, and connecting rods between the slide 75 rods on each side of the engine and the respective cranks to reciprocate the pistons in the same direction within the respective cylinders.

In testimony whereof I hereunto affix my 80 signature in the presence of two witnesses.

ROBERT H. McCARTHY.
